ALFRED L. KIRBY, OF NEWARK, NEW JERSEY.

SHEET-METAL DOOR AND THE LIKE.

1,136,238.

Specification of Letters Patent.

Patented Apr. 20, 1915.

Application filed March 21, 1912. Serial No. 685,218.

To all whom it may concern:

Be it known that I, ALFRED L. KIRBY, a citizen of the United States, residing at Newark, in the county of Essex and State of New Jersey, have invented certain Improvements in Sheet-Metal Doors and the like, of which the following is a specification.

The objects of this invention are to provide a sheet-metal door of new and improved construction; to secure maximum strength and rigidity in such a door; to provide a construction of parts which can be readily formed and conveniently and quickly assembled; to reduce the cost of manufacture without sacrificing the fireproof qualities of the door, and to obtain other advantages and results as may be brought out in the following description.

Referring to the accompanying drawings, in which like numerals of reference indicate the same parts throughout the several figures, Figure 1 shows in elevation a door of my improved construction; Fig. 2 is a vertical cross-section of the top rail of the door and adjacent portion of the panel on line A—A, Fig. 1; Fig. 3 is a horizontal cross-section of one of the side stiles of the door at its intersection with the bottom rail, taken on line B—B of Fig. 1; Fig. 4 is a similar cross section of one of the side stiles opposite a panel and showing the adjacent portion of such panel, as on line C—C, Fig. 1; Fig. 5 shows in perspective a corner of a door, broken away through the side stile, panel and bottom rail; Fig. 6 is a cross section of the molding; Fig. 7 is a perspective view of the end portion of one of the side pieces of the bottom rail, from the inside; Fig. 8 shows in perspective a certain spacing strip or stiffening bar; Fig. 9 is a perspective view of a portion of the top edge of the door, showing a certain locking strip or cap, and Fig. 10 is a sectional perspective view of the bottom part of the door, showing the locking strip or cap thereat.

In said drawings, and particularly Fig. 1, the door is shown comprising two vertical stiles 1, 1 extending the height of the door and spaced apart in parallel relation to form the longitudinal vertical edges of the door. At the top and bottom of the door, said stiles 1, 1 are joined by the top rail 2 and the bottom rail 3, respectively, and intermediate of said top and bottom rails are other rails 4 and 5 in spaced and parallel

relation to the top and bottom rails and likewise joined to the stiles 1, 1. Alternating with the said rails 2, 3, 4 and 5 are panels 6, 7 and 8, and it will be understood that all said parts, panels, rails and stiles are formed of sheet-metal as will be herein-after more fully described. Furthermore, around the edges of each panel, next to the thicker parts of the door, viz., the stiles and cross rails, are moldings, which are also formed of sheet-metal and serve to connect the panels to the stiles and rails.

As the stiles are of the same construction, though reversed in position, a detailed description of one will suffice for both, and each comprises a piece of sheet-metal bent into channel form with the two sides 9, 9 adapted to lie at the opposite sides of the door and the portion 10 between said sides adapted to form the edge of the door (see Fig. 5). The opening of the channel is toward the panels and rails and at each of the edges of the walls or sides 9, 9 the sheet-metal is folded inwardly with respect to the channel against the side or wall, as at 11, then bent away from said wall at right angles to form the shoulder or stop 12, and then bent again inward parallel to the said side or wall, as at 13.

The bottom rail consists of pieces of sheet-metal 14, 14 forming the opposite sides of the rail and having their upper edges folded inwardly and formed similar to the edges of the walls or sides 9, 9 of the stiles just described that is to say each with a folded inward portion 15, shoulder or stop portion 16 and inner portion 17 parallel to the body portion. Engaging these edges of the two pieces of sheet-metal forming the bottom rail is a molding 18, said molding having a channel portion 19 on opposite sides of which the sheet-metal is bent backwardly and away from the sides of said channel, as at 20, (see Fig. 6), and formed at its edges to interlock with the said edges of the bottom rail sides 14, 14. To this end, each edge of the molding is bent inward, as at 21, to seat upon the shoulder 15 of the bottom rail, and then bent again into the plane of the door as at 22 to lie against the portion 17 of the bottom rail, and returned parallel to itself, as at 23, to inclose said portion 17. It will be understood that said molding 18 is slid longitudinally into engagement with the side pieces 14, 14 of the bottom rail before the whole is slid into assembled engagement.

with the side stiles 1, 1. Furthermore, to brace or stiffen the sides of the rail and molding at their joints or seams, a spacing strip or stiffening bar 24 is slid inside said bottom rail and molding, see Fig. 8. This comprises a strip of sheet-metal having a portion 25 adapted to extend longitudinally of the bottom rail perpendicular to its sides 14, 14, the edges of said portion 25 being folded inward as at 26, 26 and then bent at right angles to form parallel portions 27, 27 which lie against the inner facing sides of the joints or seams between the molding and the bottom rail, said parallel portions 27, 27 being bent outwardly apart at their ends 28, 28 to hook over the stops or shoulders 22 of the molding. This strip 24 is also slid into place before the bottom rail is entered between the stiles of the door, it being understood that the flanges or members hereinafter described for joining the ends of the bottom rail to the stiles are shortened sufficiently to allow said strip 24 to enter, at least at one end of the rail. Preferably, ears 59 are bent up out of the doubled edges of the spacing strip to engage the outer sides of the joints or seams between the molding and bottom rail, as shown, and thus prevent them from spreading, also. The said parts are therefore positively and accurately positioned and spaced, along the said seams which join them together.

Each end of the bottom rail 3 has the ends of its sides 14, 14 bent and shaped similar to the edges of the strip 18 of molding already described, so as to lock with the edges of the stile 1 which have been already described. To this end each side piece 14 is first bent inwardly, as at 29, see Figs. 3 and 7, and then at right angles to lie against the portion 11 of the stile, then inward again, as at 30, to abut against the shoulder or stop 12, and then at right angles again, as at 31, to lie against the parallel portion 13, and then returned parallel to itself, as at 32, to inclose said portion 13. With this formation it will be understood that the bottom rail, carrying the molding strip 18 and spacing strip 24, can be slid into connected relation with the side stiles from their ends.

Assuming that the bottom rail 3 has thus been slid into connection with the stiles 1, 1, it is brought so that its lower edge is flush with the lower ends of the stiles, and then, a locking strip or cap 33 is inserted to close the bottom edge of the door. (See Figs. 5, and 10). To receive this locking strip 33, the lower edges of the bottom rail 3 are each bent inwardly at right angles, as at 34, then upward and returned outwardly parallel to said portion 34, as at 35, a space equal to the thickness of metal employed in the locking strip or cap 33 being left between the portions 34 and 35. The lower edges of the sides 9, 9 of the stiles are also each bent

inwardly, as at 36, and returned outwardly, as at 37, forming members similar to and in alinement with those just described upon the side pieces 14 of the bottom rail. As soon as the bottom rail is brought into proper connected relation to the side stiles, therefore, the locking strip 33 is inserted from one side of the door, the connecting portion 10 of the stile being suitably notched or recessed to permit the insertion of said locking strip. This locking strip has a central longitudinal portion 38 adapted to lie flush with the bent-in portions 34 of the bottom rail and 36 of the stiles, as shown, the metal at the edges of said middle portion 38 being bent upward and then outward parallel to said middle portion 38, as at 39, and then returned downwardly inward again, as at 40, forming members adapted to slide into hooked engagement with the members 35 upon the bottom rail and side stiles of the door and form a locked seam holding the opposite side pieces 14, 14 of the bottom rail and sides 9, 9 of the stiles rigidly in fixed relation.

When the bottom rail of the door has been thus located, the vertical moldings 41, 41 are slid into position upon the side stiles 1, 1, and the panel 8 inserted into the channels 19 of the three moldings 18, 41, 41. Said panel 95 may consist of two pieces 42, 42 of sheet-metal with any suitable filling 43 between, or it may consist of a single piece, or be otherwise composed, without departing from the spirit and scope of the invention. Above 100 the panel 8 the lower intermediate rail 5 carrying the moldings 44 and 45 and spacing strips in the manner already described, is slid into place between the stiles 1, 1, then the upright pieces 46, 46 of molding are slid 105 into place on the stiles, and the panel 7 inserted. Similarly, the upper intermediate rail 4 with its moldings 47, 48 and spacing strips is next inserted, and above it the upright pieces of molding 49, 49 and the large 110 panel 6 put in place. Then the top rail 2 with its molding 50 and spacing strip 51, as shown in Fig. 2, is slid into place between the stiles, the locking strip 52 being of course not yet inserted. Before said top locking strip 52 is inserted, vertical spacing strips 53 extending longitudinally of the stiles 1, 1 are slid into place from the top of the door, the inwardly projecting seam members 54, 54 at the upper ends of the sides 9, 9 of the stiles being suitably notched for the purpose, as at 55 in Fig. 9. These spacing strips comprise each a middle portion adapted to extend across the stile and abut at its edges the sides 9, 9 thereof, as shown in Figs. 3, 4, and 10, more especially, and from each of said edges the metal is folded backwardly inward upon itself as at 56, then away at right angles, as at 57 to lie against the inner side of 125 the seam uniting the stile with the various 130

pieces of molding and rails along its length, the metal being bent outward again at right angles, as at 58, to hook over the edge of said seam farthest from the body portion of 5 the spacing strip. After said spacing strips 53 have been inserted the top locking strip 52 is slid into place in the same manner as the locking strip 33 at the bottom of the door, and which has been described in detail.

10 The door is then completely assembled, and after having its various parts fastened together by spot-welding or other suitable means and any crevices or openings filled in any manner common to the art, it may be 15 finished and decorated as desired.

While I have described and shown in the drawings my invention as particularly applied to a door, I desire it to be expressly understood that the invention or features 20 thereof can be equally well applied to other articles, as is obvious to those skilled in the art, and as indicated by the expression "door or the like" I intend to protect my invention as applied to all articles and used in all possible places in the art of forming sheet metal, not only into doors, windows, partitions and other parts of buildings and fittings therefor, but also furniture as including all movable articles commonly embraced in that 25 30 term.

Having thus described the invention, what I claim is:

1. In a sheet metal door or the like, the combination of two hollow parts each having a margin meeting a margin of the other, one of said margins being folded backward on itself providing a doubled edge and then bent laterally at substantially right angles and then backward at right angles substantially parallel to itself, and the other margin being bent laterally in the same direction as the first-mentioned margin and then forwardly to lie against the said portion of the first-mentioned margin

which is parallel to itself and then folded 45 backward over said parallel portion, whereby said margins are united in a joint.

2. In a sheet-metal door or the like, the combination of two hollow parts each having a margin meeting a margin of the other, 50 one of said margins having a doubled edge portion a lateral shoulder and a backwardly extending portion substantially parallel to itself and the other margin having a lateral shoulder adapted to engage said doubled 55 edge of the first mentioned margin a forwardly extending parallel portion lying against said doubled portion a second lateral shoulder engaging the lateral shoulder of the first mentioned margin, and a second 60 forwardly extending parallel portion lying against the said portion of the first mentioned margin which is parallel to itself and folded backward over said last mentioned portion, whereby said margins are united in 65 a seam.

3. In a sheet-metal door or the like, the combination with parts having margins meeting in interior seams substantially parallel to each other and spaced from the walls of said 70 parts, of a spacing strip extending edgewise between the walls of one of said parts adjacent to said seam and having marginal portions returned upon itself providing a doubled edge, said returned portion being folded 75 at a distance from the doubled edges inwardly between said seams and the body portion of the strip and lying against the inner facing sides of said seams and hooking over the edges of the same away from the body of the spacing strip, said spacing strip having also ears bent out of its doubled edge at the opposite outer sides of said seams or joints.

ALFRED L. KIRBY.
In the presence of—
HOWARD P. KING,
FRANCES E. BLODGETT.
